UNITED STATES PATENT OFFICE.

WALTER EASTER HASKIN, OF FLUSHING, NEW YORK, ASSIGNOR TO PRERESSED & WELDED STEEL PRODUCTS COMPANY, OF LONG ISLAND CITY, NEW YORK, A CORPORATION OF NEW YORK.

COMBINATION IRONING BOARD AND STAND.

Application filed July 22, 1926. Serial No. 124,261.

This invention relates to combination ironing boards and stands, an object of the invention being to provide a stand which will fold flat against the board and occupy but 5 very little space when the board is not in use, inasmuch as the entire stand will fold within the length of a standard sized household board with no parts projecting beyond the ends of the board.

10 A further object is to provide an apparatus of this character which is neat and attractive in appearance, strong and durable in use, and most efficient in the performance of its functions.

15 With these and other objects in view, the invention consists in certain novel features of construction and combinations and arrangements of parts, which will be more fully hereinafter described and pointed out 20 in the claims.

In the accompanying drawings—

Figure 1 is a perspective view showing my improved apparatus in position for operation;

25 Figure 2 is a perspective view showing the apparatus partially collapsed and partially folded;

Figure 3 is a perspective view showing the apparatus entirely collapsed and completely folded.

A represents my ironing board, B and C are end frames, E is a tray connecting the end frames, and D the iron support, all of which will now be described in detail.

35 The end frame B is composed of parallel upright members 1, 1, preferably of angle iron, connected at their lower ends by a bar 2 and having a plate 3 fixed to said bars 1, 1 and located at the end of the tray E.

40 The ironing board A has a small plate 4 secured to its under face adjacent one end, and which has end flanges 5 arranged adjacent the sides of the board and to which are pivotally connected the upper ends of 45 the bars 1, as shown at 6, which allows the ironing board a free pivotal movement relative to the frame B and vice versa.

50 The iron support D preferably constitutes a metal grill pivotally connected between its ends nearer the inner end thereof to the uprights 1, 1, as shown at 7, and at its inner end is pivotally connected by links 8 with the flanges 5 of plate 4. These links 8 normally lie in substantially parallel rela-

tion to the uprights 1, 1 and prevent any 55 pivotal movement of the iron support D when the device is in operative position, as shown in Figure 1.

The end frame C is composed of angle iron uprights 9, 9, connected at their upper ends by a cross angle bar 10. This angle bar 10 has an opening 13 therein adapted to receive a pin 14 on the ironing board A when the device is in operative position.

This end frame C is appreciably shorter 65 than the end frame B and at its lower end is pivotally connected to the tray E, and a plate 15 connects the lower end of the bars 9 and co-operates with the plate 3 in forming a confining space for the articles on the 70 tray E. Tray E is also pivotally mounted at its other end to frame B as indicated at 18^a.

F represents an extension of the frame C which is also composed of upright angle 75 bars 16 and a crossbar 17 at its lower end. These bars 16 at their upper ends are connected by rivets 18 with the tray E and with the bars 9 and frame B, so that it is to be understood that these rivets constitute 80 pivots to allow the frame F to pivot relative to frame C.

The bars 1, 1 of frame B and the bars 9, 9 of frame C are connected by normally horizontal links 19, 19, which are pivotally 85 connected at their ends to the respective bars above referred to, as indicated at 20. These links and plates 3 and 15 with tray E constitute a relatively large container for articles to be ironed.

90 The end frame B at a point appreciably above the tray E is connected with the extension F by means of a pair of links 21, these links being pivotally connected to the upright bars of said frame and extension, 95 respectively, as indicated at 22.

The frame C at a point above the tray E is provided at opposite sides with laterally projecting angle brackets 23, and the frame B at a point below the tray E is provided 100 at opposite sides with similar angle brackets 24.

105 These angle brackets 23 and 24 are connected by elbow links or knuckle-jointed braces 25, the links being pivotally connected to the brackets, as shown at 26. These elbow links comprise two sections 27 and 28, pivotally connected, as shown at 29,

and having overlying tongues 30 to prevent pivotal movement in one direction beyond an alined position of the link sections and function to prevent collapse of the apparatus 5 when once positioned for use.

The operation is as follows:

Figure 1 shows the apparatus in operative position, Figure 2 shows a convenient manner of folding the supporting frame, 10 and Figure 3 shows the apparatus completely folded.

To fold or collapse the frame, the ironing board is lifted sufficiently to draw the pin 14 out of the opening 13, and the links 25 15 are broken, moving the pivot points 29 upwardly. This is accomplished preferably after the ironing board is tilted over and supported with one end of the ironing board resting on the floor somewhat in the position indicated in Figure 2. When the parts 20 are in this position, a downward pressure on the lower end of the end frame B and an upward movement of the lower end of the frame extension F will cause the several 25 parts to swing so as to lie flat against each other, as shown in Figure 3. During this movement of the several parts the iron support D will be caused to swing to a position between the bars 1, 1 of frame B so that the 30 entire frame will lie flat and against the board, as clearly indicated in Figure 3.

It is desirable to have the board so that its free end can be elevated to allow skirts and other articles to be slid over the board, 35 and this can be readily done by elevating the free end of the board so as to draw the pin 14 out of the opening 13.

Various slight changes and alterations might be made in the general form of the 40 parts described without departing from my invention, and hence I do not limit myself to the precise details set forth but consider myself at liberty to make such slight changes and alterations as fairly fall within the 45 spirit and scope of the appended claims.

I claim:

1. In combination with an ironing board, an end frame pivotally connected to the ironing board, a tray pivotally connected at one end to said end frame intermediate the ends of said frame, a second end frame pivotally connected at one end to the other end of the tray and detachably connected with and supporting an intermediate portion of the ironing board, a frame extension 55 pivotally connected to the tray and in substantial alinement with the last-mentioned end frame when in operative position, knuckle-jointed braces pivotally connecting the end frames, links connecting the first 60 mentioned end frame and said extension, said knuckle-jointed braces adapted when collapsed to permit the end frames and extension frame to lie substantially flat and parallel to the tray and ironing board, the detachably connected end frame being released 65 when the board is to be folded.

2. In combination with an ironing board, an end frame pivotally connected to the ironing board, a tray pivotally connected 70 at one end to said end frame intermediate the ends of said frame, a second end frame pivotally connected at one end to the other end of the tray and detachably connected with and supporting an intermediate portion of the ironing board, a frame extension 75 pivotally connected to the tray and in substantial alinement with the last mentioned end frame when in operative position, knuckle-jointed braces pivotally connecting the end frames, links connecting the first 80 mentioned end frame and the extension of the other end frame, the knuckle-jointed braces and the detachable end frame being adapted when collapsed to permit the end 85 frames and extension frame to lie substantially flat and parallel to the tray and ironing board, plates on the end frames located at the ends of the tray and pivoted links connecting the end frames at points adjacent 90 the upper ends of the plates.

WALTER EASTER HASKIN.
